UNITED STATES PATENT OFFICE.

FREDERICK W. WOOD, OF KANSAS CITY, MISSOURI.

PNEUMATIC ACTION FOR MUSICAL INSTRUMENTS.

No. 821,568.

Specification of Letters Patent.

Patented May 22, 1906.

Application filed June 13, 1905. Serial No. 265,111.

To all whom it may concern:

Be it known that I, FREDERICK W. WOOD, a citizen of the United States, residing at Kansas City, in the county of Jackson and State of Missouri, have invented certain new and useful Improvements in Pneumatic Actions for Musical Instruments, of which the following is a specification.

This invention relates to pneumatic actions for musical instruments, and has for its object to produce a diaphragm construction which operates noiselessly under the impact of the valve which cuts off communication between the pneumatics and the exhaust-chamber.

A further object is to produce a diaphragm construction which guards against any possibility of air-leakage following the action of the valve above referred to.

Still further object is to produce a diaphragm construction which is less expensive in its construction and maintenance than that commonly employed in pneumatic actions for what are known as "automatic" pianos or piano-players.

To these ends the invention consists in certain novel and peculiar features of construction and combination of parts, as hereinafter described and claimed, and in order that it may be fully understood reference is to be had to the accompanying drawings, in which—

Figure 1 is a top plan view of the pneumatic action with that portion superposed with relation to the exhaust-chamber omitted, said figure showing two diaphragm structures—one complete and the other with the diaphragm proper and block carried thereby omitted. Fig. 2 is a vertical section on the line II II of Fig. 1, but different from the latter by showing the diaphragm proper and the block carried thereby. Fig. 3 is a detail perspective view of the removable diaphragm construction.

Referring now to the drawings in detail, 1 indicates the bottom board of the pneumatic-action mechanism; 2, the pneumatics underlying the same; 3, the passages leading from the pneumatics and adapted to connect through the valve-chambers (not shown) with the exhaust-chamber 4.

5 represents passages (one only appearing in the bottom board) and connected at their outer ends by tubes 6 to the tracker-bar, (not shown,) each passage 5 being provided with a fine partitioning-screen 7 to exclude from the valve mechanism (not shown) any

small foreign particles which may be drawn into the tracker-bar, and connecting each passage 5 with the exhaust-chamber between the screen and diaphragm is a vent-passage 8.

9 indicates blocks secured by screws 10 upon the bottom of the exhaust-chamber, a thin packing-strip 11, secured by preference to the bottom of the block, making the connection of said block with the bottom of the exhaust-chamber air-tight around passage 5. Said block has a central perforation 11^a, which extends through said packing-strip 11 and communicates with passage 5. The block is also provided with a recess 12 in its upper side, and secured in any suitable manner upon the base of said recess is a cushion 13, having a central aperture 14 forming a continuation of perforation 11^a.

15 indicates a diaphragm of rubber, bridging the recess of the block and covering its upper side at opposite ends of the recess, as at 16, and its sides, as at 17, said diaphragm being secured to the block in any suitable manner, so as to make an air-tight connection therewith, the screws 10 also extending through the diaphragm, so as to assist in securing the same to the block.

18 is a block secured to the upper side of the diaphragm by elastic material, and 19 is a sound-deadening cap secured to the top of the block, said cap being preferably of leather and adapted to receive the impact of the valve-stem (not shown) when the valve descends to close communication between its pneumatic and the exhaust-chamber. Commonly in pneumatic-action mechanism the diaphragm is in the form of a strip of rubber, extending the full length of the exhaust-chamber and bridging cavities in the bottom thereof vertically above each passage 5, and should the diaphragm leak at any point it is necessary to remove it and in so doing to also remove other superposed parts which serve to hold it in position. With my improved diaphragm construction it will be

seen that there is a separate and distinct diaphragm for each passage 5, and if it is found that any diaphragm is defective it can be quickly and easily removed by simply withdrawing screws 10. The pneumatic-action mechanism can then be quickly and easily restored to operative condition by replacing the diaphragm removed with a new one and by a "new" one is meant the structure represented by Fig. 3, because it is cheaper to throw the defective diaphragm away than to

remove the diaphragm proper, 15, from the block 9 and equip the latter with a new one.

When the valve depresses the diaphragm, as shown in Fig. 2, the cushion 13 makes the impact of block 18 noiseless, and, furthermore, permits said block to seat itself so snugly that leakage of air between the cushion and that portion of its diaphragm proper underlying the block is impossible, and it will 10 also be noticed because the sharp edges of the block are rounded there is no appreciable wear on the diaphragm to shorten its period of service.

From the above description it will be apparent that I have produced a pneumatic action for musical instruments possessing the features of advantage enumerated as desirable and which obviously is susceptible of modification without departing from the principle of construction involved.

Having thus described the invention, what I claim as new, and desire to secure by Letters Patent, is—

1. A device for use in pneumatic actions for musical instruments, comprising a block having a central perforation and a recess, the latter being the full width of but terminating short of the ends of the block and communi-

cating centrally with said perforation, and a diaphragm bridging said recess and secured at its ends to the ends of the block and at its sides to the side edges of the block and forming a chamber between it and the upper side of the block, which is air-tight except through the perforation of the latter.

2. A device for use in pneumatic actions for musical instruments, comprising a block having a central perforation and a recess, the latter being the full width of but terminating short of the ends of the block and communicating centrally with said perforation, a diaphragm bridging said recess and secured at its ends to the ends of the block and at its sides to the side edges of the block and forming a chamber between it and the upper side of the block, which is air-tight except through the perforation of the latter, and a block secured to the upper side of the diaphragm and capable of sinking into the recess of the first-named block.

In testimony whereof I affix my signature in the presence of two witnesses.

FREDERICK W. WOOD.
